[57] ABSTRACT

The use of 10-methyl- $\Delta^{1,9}$ -octalone-2 as an olfactory component in odorant compositions is disclosed.

1 Claim, No Drawings

NOVEL ODORANTS

FIELD OF THE INVENTION

This invention relates to the field of fragrances.

DESCRIPTION OF THE PRIOR ART

10-Methyl- -octalone-2 of the formula

is known, for example, from J. Chem. Soc. 53-60 (1937) [see also J. Org. Chem. 29, 2501-2505 (1964)].

SUMMARY OF THE INVENTION

It has now been surprisingly found in accordance with the present invention that 10-methyl- -octalone-2 possesses particular odorant properties which make it excellently suited as a component of odorant compositions.

The present invention is based on the foregoing finding and is concerned, in one of its aspects, with odorant compositions which contain 10-methyl- -octalone-2.

In another of its aspects, the present invention is concerned with a method of imparting an odor to materials by applying thereto or incorporating therein an odor-imparting amount of 10-methyl- -octalone-2.

In yet another of its aspects, the present invention is concerned with a process for altering the perfumistic properties of odorant compositions by incorporating 10-methyl- -octalone-2 into an odorant composition.

The fragrance of the octalone of formula I is "agreste," balsamic and hay-like. It displays, in particular, honey-like, tonka- and coumarin-like, sweet-iris-like, spicy and slightly woody notes reminiscent of light tobacco.

DESCRIPTION OF THE PREFERRED EMBODIMENTS

The octalone of formula I can be used in the manufacture of compositions having a wide variety of perfu-

mistic applications. In particular, it can be used as a component of perfume bases for modern men's lines. Furthermore, the character of compositions having, for example, floral notes, especially those having jasmine, rose or muguet character, can be altered or strengthened with the aid of the octalone of formula I. The same is also true of perfume bases having wood, chypre or fouger character, the perfumistic notes of which are influenced in a desirable manner by the incorporation therein of the octalone of formula I.

Finally, the octalone of formula I also has a fixative action.

The amounts in which the octalone of formula I can be used in odorant compositions can vary within wide limits. In perfume bases, the octalone can be employed, for example in amounts of ca 2-20 wt.% and in finished products such as perfumes, lotions etc. about 1-2% can be present. For the perfuming of technical products, for example of solid and liquid detergents, synthetic washing agents, aerosols or cosmetic products of all kinds (e.g. soaps), there can in general be employed ca 0.1-0.3% (in washing agents) or 0.8-2% (soaps) of such perfume bases.

The following Example illustrates the present invention, without however being limitative thereof.

Odorant composition (lavender type):

	parts by weight:
30	cinnamon oil Ceylon
	5
	geranium oil Bourbon
	5
	musk ambrette
	5
	vanillin (10% in diethyl phthalate)
	5
	geraniol pure
	20
	phenylethyl alcohol
	30
	nonyl acetate
	30
	bergamotte oil Reggio
	50
35	lavandin 22/24%
	100
	lavender oil 38/40%
	300
	550

The addition of 5-10 wt.% of the octalone of formula I to this composition imparts thereto a fuller, warmer note and the lavender character of the composition is decisively intensified.

What is claimed is:

1. An odorant composition which contains an olfactory-effective amount of 10-methyl- -octalone-2 and at least one carrier commonly used in odorant compositions.
